STORAGE AND RECLAIMING SYSTEM

Filed May 1, 1926

WITNESS:

John P. Kitchel.

INVENTOR

Robert H. Beaumont
BY
Augustus B. Swoughton
ATTORNEY.

UNITED STATES PATENT OFFICE

ROBERT H. BEAUMONT, OF RADNOR, PENNSYLVANIA, ASSIGNOR TO R. H. BEAUMONT COMPANY, OF PHILADELPHIA, PENNSYLVANIA, A CORPORATION OF PENNSYLVANIA

STORAGE AND RECLAIMING SYSTEM

Application filed May 1, 1926. Serial No. 105,997.

The principal object of the present invention is to avoid the expenditure of excess power and the rapid wear on the return cable due to its cutting into material and being buried therein. Another object of the invention is to scrape material deposited at a point on the margin of the storage area and store it over the area and also to reclaim material from any part of the area and deposit it at the point on the margin of the area. Another object of the invention is to provide an improved storage and reclaiming system adaptable to many commercial conditions and economical and durable in use and effective over substantially all of the available storage area.

Other objects of the invention will appear from the following description at the end of which the invention will be claimed. However, reference will be made to the accompanying drawing of which the single figure is a diagrammatic view illustrative of a storage and reclaiming system embodying features of the invention.

In the drawing 1 is a storage area of which the shape or outline is not material. 2 is a drag scraper. 3 is a winding machine. 4 is a front post. 5 is a front or pulling cable and it leads from the front post 4 to the winding machine 3 and to the scraper 2. 6 is a track arranged around the margin of the area 1, or, more accurately, partway around the margin of that area. 7 is a tail block car on the track 6. 8 and 9 are sheaves or sheave equipment located at fixed points around the margin of the area 1 or, more accurately, around a portion of the margin of that area. 10 is a return cable guided by the tail block car and sheave equipment from the scraper 2 to the winding machine 3 clear of the front post 4 and of the material in the area.

When the tail block car 7 is on the portion of the track 6 between the sheaves 8 and 9, the return cable 10 passes from the car 7 around the sheave 9 to the winding machine 3, and when the tail block car 7 is on the portion of the track as in the drawing the return cable 10 passes around the sheaves 8 and 9 as shown. In all cases the return cable 10 is kept out of the material handled and

this is important because if the return cable cuts into the material and is buried, there results waste of power and rapid wear. The front or pulling cable 5 and the portion of the return cable 10 on the scraper side of the tail block car 7, if any, are kept on the surface of the material by the reciprocating action of the scraper.

By way of further description it may be said that material, for example, coal is reclaimed back to the hopper 11 located in front of the front post 4, and from this hopper 11 the coal flows back to the lifting means 12 which deliver it into railway cars on the railway line 13 or elsewhere. The same lifting means are available for raising material from the track hopper 14 under a railroad car on the line 13 and for chuting it into an initial pile indicated at 15. The winding machine 3 is of course located outside of the area 1 and it may well be spaced between the front post 4 and the sheave 9. It is an advantage of the described construction that the scraper 2 can work all over the storage yard or area whether the storage area be defined by a track 6 constituting a radial or other path.

It will be obvious to those skilled in the art to which the invention relates that modifications may be made in details of construction and arrangement and in matters of mere form without departing from the spirit of the invention which is not limited to such matters or otherwise than as the prior art and the appended claims may require.

I claim:

1. A storage and reclaiming system embodying a storage area, a drag scraper, a winding machine, a front post, a front or pulling cable leading from the front post to the winding machine and to the scraper, a track arranged around the margin of the area, a tail block car on the track, sheave equipment located at fixed points around the margin of the area, and a return cable guided by the tail block and sheave equipment to the winding machine and drag scraper clear of the front post and of the material in the area.

2. A storage and reclaiming system embodying an area for the storage of material, a

winding machine, a drag scraper, a cable for reciprocating the scraper, a tail block, and means arranged around the margin of the storage area for guiding the return reach of the cable between the winding machine and the tail block clear of the material on said area.

3. A storage reclaiming system including a scraper, a storage area, a winding machine, a front post and tail block for guiding the reciprocation of the scraper over the area, a front cable passing around the front post to the winding machine, sheave equipment arranged clear of the margin of the area and interposed between the tail block and winding machine, and a return cable passing from the winding machine around the tail block and guided between the tail block and winding machine by the sheave equipment clear of the storage area.
